EXPLOSIVE LOAD FOR MINES

Guillaume Weber, Mondorf-les-Bains, Luxembourg; vested in the Alien Property Custodian

Application February 17, 1939, Serial No. 257,008
In Luxembourg February 18, 1938

5 Claims. (Cl. 102—24)

The present invention relates to an improved construction of an explosive load for mines and the like.

Explosive loads for mines are known which consist in a priming-cartridge, an explosive substance and a water cartridge, the instantaneous evaporation of the water being effected by the great heat developed by the priming-cartridge when it explodes. In certain cases, metallic powders, iron filings or clippings are added to the water or to the substances impregnated with water. This arrangement negatives the effect of these substances, since they are immersed in the water and cannot work as efficiently as they would if they were separated from the water and directly connected with a source of heat.

The loading tube or case is preferably made of paper, linen or similar fibrous substances in order to facilitate the introduction, into the blasthole, of a load of several cartridges and thus avoid losses of the explosive substance in the clefts of the ground.

The present invention has for its object certain improvements in and relating to the explosive loads for mines and consists in introducing the explosive cartridges of any sort, comprising those with liquid oxygen, into a special tube or case containing metallic and combustible powders. The metallic powders are either coated on the interior surface of the tube, or they are lodged between one or more spirals of the tube or mixed with other substances between two or several spirals of the tube.

They can also be incorporated in the paper ply when the tube is being manufactured.

Figure 1 is a perspective view of a portion of a tube, the interior surface of which is coated with metallic powders.

Figure 2 is a cross sectional view of a modified arrangement showing metallic powders lodged between one or more spires of a paper tube.

Figure 3 is a cross sectional view of a further modification in which spongy inactive incombustible substances are impregnated with water or cooling salts.

Figure 4 is a sectional view through a tube blank with metallic powders incorporated therein.

The combustible powders used can be alumina.

The combustible powders used can be aluminum, magnesium, silicon, calcium, iron, silicium of these powders. The combustible powders will advantageously be mixed with metallic oxides, for instance with oxides of iron or with other substances which hasten the oxidation process.

By using the loading tubes according to the

present invention, the explosive power is not only increased, but the combustion of the particles of the explosive substance is more complete and the noxious smokes are avoided.

5 The loading tubes are also fit for the explosive loads with cartridges containing water or substances impregnated with water. The water can also be present in combination with other substances or in the form of a colloidal dispersion. 10 Through the great heat produced by the priming cartridge and the metallic powders of the loading tube at the moment of the deflagration, the water is instantaneously gasified and the gaseous volume and thus the power of the explosive load is increased.

15 The dislocation of the ground being the same, the explosive load can be reduced by using water cartridges; the quantity of smoke is also reduced in a proportion at least equal to the reduction 20 of the explosive load. Through the use of the special loading tube, the workmen, when working underground, are not any more inconvenienced by the smoke, as is generally the case when using dynamites, cheddites, compressed powders, etc., without any special loading tube.

25 It is possible to return almost immediately to the working place if the loading tubes according to the present specification are utilized.

When used in coal-pits rendered more or less 30 dangerous by fire-damp or dust, the metallic powders of the tube are partially or totally replaced by other powders, like certain carbonates or other substances fit to extinguish fire.

35 The water cartridges used in the coal-pits will contain inactive, incombustible absorptive substances, such as infusorial earth, ground slag, magnesia carbonate, etc., preferably mixed with cooling salts. The explosive loads thus constituted and combined with the ordinary safety explosive substance warrant a maximum of security 40 in the coal-pits rendered dangerous by fire-damp or dust.

45 The explosive loads contained in special tubes or cases, according to the present invention, are also fit to be used for the felling of material in large quantities in mine-rooms or through use in vertical holes of a large diameter, and with water cartridges in the quarries where an intermediate stuffing is used.

50 According to the foregoing and in reducing the invention to practice as shown in Fig. 1, the metallic powders are coated on to the inside of a cylindrical tube which is preferably made of paper, while according to Fig. 2 the paper tube is spiraled and the metallic powders are lodged

between one or more of the spirals. In the form shown in Fig. 3, spongy inactive incombustible substances impregnated with water or cooling salts are lodged between two or more spirals of the tube. In Fig. 4 there is shown a tube blank in which the metallic powders are incorporated therein. From this blank the tube can be rolled into shape and present much the same appearance as that tube shown in Fig. 1.

I claim:

1. An explosive cartridge comprising an inner core of explosive material and an outer fibrous wrapper surrounding said core and being impregnated with at least one finely-divided, combustible metallic powder.
2. An explosive cartridge comprising an inner core of explosive material and an outer fibrous sheet wrapped in layers around said core, said

fibrous sheet being impregnated between said layers with a finely-divided, combustible metallic powder.

3. An explosive cartridge comprising an inner core of explosive material and an outer fibrous wrapper surrounding said core, said wrapper being impregnated by a mixture of a finely-divided, combustible metallic powder and a metallic oxide reactive with said metallic powder.
4. An explosive cartridge as claimed in claim 1 wherein the combustible metallic powders constitute a coating on the inside of the wrapper.
5. An explosive cartridge as claimed in claim 1 including a cartridge consisting of a spongy substance impregnated with water and disposed within the wrapper.

GUILLAUME WEBER.
